UNITED STATES PATENT OFFICE

HARRY G. MELCHER, OF GROVE CITY, PENNSYLVANIA, ASSIGNOR OF ONE-HALF TO
JOHN G. CARRUTHERS, OF GROVE CITY, PENNSYLVANIA

HEAT EXCHANGER

Application filed September 9, 1932. Serial No. 632,353.

This invention relates to improvements in heat exchangers, more particularly to devices providing for exchange of heat between separate and independent flow streams, to either 5 effect a cooling of one of the streams, as for example, oil, or the heating of the stream where it is desired to pre-heat liquid flowing to a boiler or other container.

It is among the objects of the invention to 10 provide a heat exchanger of simple, compact and durable construction which shall consist of a plurality of cast sections of like construction which are joined in numbers determined by the capacity it is desired to obtain 15 in the heat exchanging unit.

A further object of the invention is the provision of a flow system in a heat exchange device which shall be highly efficient in its operation, which shall be designed to 20 set up turbulence by splitting the flow in the flow system and which shall be further designed to direct the flow of the fluids relative to each other in such manner as to produce the most efficient exchange of heat.

25 A further object of the invention is the provision of means for providing for the complete submersion of one of the flow channels in the other whereby one of the flow streams completely surrounds the other flow stream, and still a further object of the invention is the provision of means for regulating the flow of fluids from the communicating ports through the flow passages in a manner to produce maximum turbulence in the flow 30 stream.

These and other objects of the invention will become more apparent from a consideration of the accompanying drawings constituting a part hereof in which like reference characters designate like parts and in which Figure 1 is a longitudinal sectional view of a heat exchanger embodying the principles of this invention; Figure 2 a cross-sectional view thereof taken along the line 40 II-II of Figure 1; Figure 3 a cross-sectional view taken along the line III-III of Figure 1; Figure 4 an end elevational view of a modified form of the invention; Figure 5 a cross-sectional view taken along the line 45 V-V of Figure 4; Figure 6 an end elevational view of still another modification of which Figures 7 and 8 are cross-sectional views taken along the lines VII-VII and VIII-VIII of Figure 6; Figure 9 an end 50 elevational view of still another form of the

invention of which Figures 10 and 11 are cross sections taken along the lines X-X and XI-XI of Figure 9; Figure 12 a cross-sectional view of a plurality of assembled sections of modified form of the plate shown in Figure 1; Figure 13 an end elevational view of a spiral form; and Figures 14 and 15 an end elevational and cross-sectional view, respectively, of still another type of plate.

With reference to the structure shown in 60 Figures 1 to 3 of the drawings, the elements therein illustrated comprise a series of plates generally designated by the reference numeral 1, the plates being preferably cast and having cored-out passages 2 of annular 65 form and axial passages 3, the passages 2 being rendered communicative through a series of ports 4 and through vent openings 5.

The cast plates 1 are assembled in the manner shown in Figure 1 by mounting them on 70 a threaded stud or rod 6, there being as many of the plates assembled together as are necessary to provide sufficient capacity to effect a suitable exchange of heat at a given rate 75 of flow of the fluid in a manner to be hereinafter explained.

The ends of the series of plates 1 are provided with plates 7 and 8 having cored passages or ports 7a and 8a, respectively, and 80 passages 7b and 8b, respectively. The ends 85 of rods 6 are provided with screw threads 9 for receiving screw nuts 10 which when drawn up on their threads, press the plates 1 between the end members to securely hold them in position.

The plates are assembled in the manner shown with gaskets 1a disposed between adjacent plates and by arranging their ports 4, 180° apart, the annular passages 2 are rendered communicative with the end passages 95 7a and 8a. The "through" passages 3 communicate with the end passages 7b and 8b.

In operation, the heat exchanging unit is connected with the ports 8a communicating with the source of fluid, such as oil, as for 100 example in an automotive vehicle engine, and the port 8b is connected to a source of cooling water such as the radiator of an automotive vehicle engine.

When so connected, the fluids will pass 105 under the pressure of the pump in the system through their respective flow passages, the oil flowing through the port 7a into the port 4 of the annular passages 2 and from one annular passage to another through suc- 110

cessive ports 4 until it passes through the opposite port 8a back into the lubricating system. Similarly, the cooling medium or water flows in at one of the ports 8b and 5 along and around the axial flow-passages 3 and out through the other port 8b.

The vents 5 prevent the flow passage 2 from being air bound and further permit draining the unit when its application to another kind of fluid is desired.

With reference to the structure shown in Figures 4 and 5 of the drawings, the inlet and outlet ports are illustrated by the reference numerals 11 and 12, respectively, and it is to be noted that the ports are on the outside of the plates so as to assure that there will be no intermingling of the fluid passing through the respective conduits. In the structure of Figures 4 and 5 the annular flow passages 13, 13a and 13b and the axial flow passages 14 are arranged in a manner similar to the passages 2 and 3 of Figures 1, 2, 3, inclusive, of the drawings, being however a multiple of passages which are intercommunicating through common flow chambers 15 and 16. The flow of the fluid entering the port 11 is radially inward toward the annular passages 13, 13a and 13b, as indicated by the arrows and the location of the flow chambers 15 and 16 on opposite sides of the annular passages causes the flow to be divided in two directions. By gradually reducing the width of the flow chamber 15 and gradually increasing the width of the flow chamber 16 the fluid will flow at substantially equal velocities through the several annular passages 13, 13a and 13b. The dividing of the flow in the manner indicated causes a turbulence of the fluid which is desirable in that it assures proper circulation of the fluid through the heat exchanger plates and also makes for a more efficient exchange of heat between the fluid in the annular passages and the fluid in the axial passages.

In Figures 6 to 8 inclusive of the drawings, the flow passages 17 and 17a communicate with ports 18 and 19, the ports being disposed midway between the two annular passages, and the axial passages 20 are disposed to direct the flow of the cooling medium completely around the annular passages, which is also the case in the structure disclosed in Figures 4 and 5 of the drawings. By so directing the flow, a maximum efficiency in the exchange of heat is produced between the respective flow passages.

With reference to the structures disclosed in Figures 9 to 11 inclusive of the drawings, the tubular passages 21 and 21a communicate with a flow chamber 22 which constitutes a passage between annular passages 21 and 21a. Ports 24 and 25 are provided to constitute inlets or outlets as the case may be and if the fluid is directed to enter the port 24 it will flow through divided paths in the

annular passage 21, thence to the flow chamber 22 into the annular passage 21a, thence out through the port 25 and vice-versa if the port 25 were constituted the inlet passage and port 24 the outlet passage. In Figures 9 to 11 inclusive of the drawings, the reference numerals 26, 26a, and 26b designate the axially disposed passages of the cooling or heating medium, as the case may be.

It will be noted in Figure 10 that the annular flow passages 21 and 21a are relatively small in proportion to the ports 24 and 25 and for this reason the flow of oil or the like to the annular passages is uniformly divided and turbulence is produced where the flow streams meet.

In Figure 12 of the drawings, the plates 28 are formed with annular slots or grooves 29 which are open at one end and which when assembled in the manner shown, form annular flow passages. Gaskets 30 are disposed between the plates and are cut out as at 31 to correspond to the grooves 29 and other flow passages.

Plates 28 are provided with ports 32 which when staggered 180° apart cause a divided flow through the annular passages 29, as hereinbefore explained. Plates 28 are provided with axial flow passages 33 and 33a.

In Figure 13 of the drawings, the flow channel 34 is in the shape of a spiral with ports 35 and 36 at the respective ends thereof. Ribs or webs 37 connect the flow channel with the outer wall 38. This type is less efficient than the annular type of flow channel as the flow is in one direction because of the location of the ports at the ends thereof.

With reference to Figures 14 and 15 of the drawings, the plates illustrated are similar to the plates of Figures 4 to 8 of the drawings in that the annular flow channel 39 is completely surrounded by the fluid of the axial channel 40. A single annular channel is employed instead of the multiple channels of the structures shown in Figures 4 to 8 of the drawings.

In the structures disclosed in Figures 1 and 12 of the drawings, the annular flow passages are surrounded on two sides by the medium flowing axially of the unit, and in the remaining figures of the drawings the annular flow passages are completely surrounded by the fluid with which it is desired to effect the exchange of heat with the fluid in the annular passages. It is, of course, obvious that the latter construction is more efficient and would be productive of a higher rate of exchange of heat within a given space.

The structure shown in Figures 1 and 2 is illustrated as made up of individual plates, but it may, of course, be possible to cast an integral unit with cored out passages within the spirit of this invention.

In all of the structures shown, with the exception of that of Figure 13, in which the

flow passages are spiral, the inlet and outlet ports are located in such manner that the flow to the annular passages is in opposite directions which increases the efficiency, and 5 furthermore causes a turbulence of the fluid in the annular passages adjacent the ports at the point where the flow streams meet. The turbulence in the fluid is a desirable feature since the agitated fluid effects a greater 10 exchange of heat with its surrounding wall, and with the construction herein employed, turbulence is attained to a high degree.

From the multifarious designs herein disclosed in the numerous figures of the drawings, 15 it is apparent that the principle of the invention is applicable to a large number of forms, and applicant does not wish to be limited to the specific forms herein disclosed as various modifications may be made in the 20 details of construction without departing from the principles herein set forth.

On account of the compactness of the exchange unit and the construction of the plates which in most cases may be cast, but which 25 may be constructed in any other manner, a heat exchanger of relatively large heat exchange capacity may be constructed within a sufficiently restricted space to be applicable for use in the cooling of the lubricating oils 30 for automobile vehicle engines and for other kindred uses such as the cooling of transformer oils and the like.

Although the invention has been described as for use in cooling oils or the like, it will 35 obviously be applicable for heating purposes or for any use where it is designed to effect an exchange of heat between two streams of liquid or gases as the case may be.

I claim:

1. A heat exchanger comprising a plate 40 having an annular flow passage therein in heat exchange relation with one or more axial passages, said annular passage having communicating inlet and outlet ports in staggered relation whereby the flow of fluid is divided in said passages and said annular and axial passages having connections at the ends of said plate for sources of fluid supply.

2. A heat exchanger comprising a plate 45 having one or more annular passages and axial passages disposed between said annular passages, said annular passages having ports spaced to cause fluid to flow in divergent paths and said axial passages being communicative around the walls of said annular passages whereby the fluid flowing axially of 50 said exchanger plates completely surrounds the wall of the annular flow passages.

3. A heat exchanger comprising a plate 55 having annular passages in radially spaced relation and having axially disposed passages between said annular passages, said annular passages being isolated from said axial 60 passages and having connecting flow cham-

bers with communicating inlet and outlet ports, said flow chambers being graduated to provide a substantially equal flow of liquid through the respective annular passages, irrespective of their distance from the inlet or 70 outlet ports.

4. A heat exchanger comprising a plurality of plates having annular flow passages and having common connecting ports disposed between said passages, said annular 75 passages having axial passages disposed therebetween and extending therearound whereby said annular passages are completely surrounded by the fluid flowing in said axial passages and the inlet and outlet ports of said annular passages being in spaced relation whereby the fluid is divided in its flow from the inlet passages to the outlet 80 passages and whereby the fluid is subjected to turbulence.

5. A heat exchanger comprising a plurality of plates having annular flow passages in radially spaced relation, said passages communicating at one end by a flow chamber and having ports at the other end, axial passages 90 disposed between said annular passages and radial passages communicating with said axial passages whereby the annular passages are completely surrounded by the fluid passing through the axial passages, the ports of 95 said annular passages being so arranged that the fluid flowing into one port will be divided and flow through the annular passages, thence through the flow chamber between the annular passages, and again through the annular 100 passages to the outlet port.

6. A heat exchanger comprising a flow channel in the form of a series of annular 105 passages, each passage having inlet and outlet ports communicating with the next adjacent passages, and all of said annular passages having common axially disposed passages and in heat exchange relation therewith, the inlet and outlet ports of said annular 110 passages being spaced to divide the flow into divergent paths through said annular passages.

7. A heat exchanger comprising a flow channel in the form of a series of annular 115 passages, each passage having inlet and outlet ports communicating with the next adjacent passages, and all of said annular passages having common axially disposed passages in heat exchange relation therewith, end plates secured to said flow channels and means in said end plates for connecting the same to fluid circulating systems whereby one fluid flows angularly through said annular flow channel and another fluid flows 120 in a substantially straight line through said axial flow passages.

In testimony whereof I have hereunto set my hand.

HARRY G. MELCHER.
